UNITED STATES PATENT OFFICE.

GEORGE BURROWS, OF LIVERPOOL, ENGLAND.

DRESS-PLACKET FASTENER.

No. 813,945.

Specification of Letters Patent.

Patented Feb. 27, 1906.

Application filed July 14, 1904. Serial No. 216,619.

To all whom it may concern:

Be it known that I, GEORGE BURROWS, commercial traveler, a subject of the King of Great Britain, and a resident of Liverpool, 5 in the county of Lancaster, in the Kingdom of England, have invented certain new and useful Improvements in or Relating to Dress-Placket Fasteners, (for which application has been made in Great Britain, No. 21,201, 10 dated October 3, 1903,) of which the following is a specification.

This invention has for its object a dress-placket fastener whereby the placket can be opened by hand, will remain open, and on 15 closing will hold fast automatically, requiring a considerable pull beyond what would accidentally come upon the dress to open it again.

In the accompanying drawings, Figure 1 is a 20 view of the fastener open applied to a dress-placket; Fig. 2, the same closed; Fig. 3, an edge view of the fastener separated from the skirt; Fig. 4, a perspective view thereof.

A fastening device constructed in accordance with the present invention comprises a primary and an auxiliary member A and A', respectively. In constructing the primary member A, I employ a springy cheek or blade a, and in constructing the auxiliary member 25 A', I also employ a springy cheek or blade a'. The primary flexible blade a is provided with a stirrup e, which carries primary right-angled extensions b and also a substantially flat spring d. The auxiliary blade a' is pivotally mounted upon extensions b, and owing to the 30 positioning of spring d upon blade a the same retains the blades closed together or wide opened, respectively. The blade a' is adapted to be moved laterally with respect to the 35 primary blade a. The stirrup e carries spring d and is drilled with apertures f upon its lower end. The auxiliary blade a' has a finger g, against which the spring d presses, and tends to make the blades after passing a 40 certain angle fly together when being closed or fly open after passing said angle when being opened. At a point where the two blades are partly open this projection presses against the spring and puts the highest pressure 45 upon it; but on either side of this point the pressure is relieved. The result is that the spring, which constitutes cushioning means, always has a strong tendency to keep the two blades closed while they are closed, as in a 50 closed position there is least pressure on the

spring and increased pressure up to a certain point of opening of the blades, after which the pressure is reduced, so that beyond that point the blades tend to stand wide open. It will be obvious that the finger g engages the 60 portion of the spring d which projects into the rectangular opening of the stirrup carried by the primary blade a and that the finger slides longitudinally over the spring when lateral movement is imparted to the blade. 65

In use the two blades are placed at the edge of the placket i with the hinge at the bottom where the slit ends, the hinged end being fastened in place by sewing the material to the holes f, and the other ends of the blades are 70 fastened to the waist-belt k of the skirt by sewing it to the holes c, the edges of the placket being hemmed over the blades throughout their length. When it is desired to put on the petticoat or skirt, the placket 75 is opened by hand and will remain open to admit of the wearer putting it on. Then on closing the placket the fastener will hold the slit fast automatically, and the placket cannot separate with a considerable pull beyond 80 what would accidentally come upon the dress to open it.

The two springy cheeks or blades a and a', which are hinged together, are provided with stirrups e and e', said stirrups being preferably formed of non-springy material. The stirrup e of primary blade a carries the spring 85 d, which projects into the rectangular opening h, and the stirrup e' is provided with a finger g, which works against the spring d, so that at the point where the primary and auxiliary blades are partly opened the spring 90 has the highest pressure exerted upon it; but upon either side of this the pressure is relieved. It will be obvious that the stirrups 95 are secured to the blades near their lower end.

It is obvious that in cases where a bustle or dress-improver is worn to expand the body of the skirt below the waist that the blades 100 can be formed in a suitable curve, so as to correspond with the outward curve of the improver.

I declare that what I claim is—

1. In a device of the character described, 105 the combination of a primary blade, a stirrup having an opening secured to said blade, said stirrup provided with parallel, right-angled extensions and a spring, an auxiliary blade provided with a stirrup pivotally mounted 110

upon said extensions, said auxiliary stirrup provided with a finger, and said finger normally in engagement with said spring.

2. In a device of the character described, 5 the combination of a flexible, primary blade, a stirrup having a rectangular opening secured to said blade, an angular spring secured upon said stirrup and partly closing and extending into said opening, said stirrup 10 provided with parallel, right-angled extensions, an auxiliary flexible blade provided with a stirrup pivotally mounted upon said parallel extensions, said auxiliary blade provided with a finger, said finger extending into 15 the rectangular opening of the stirrup secured to the primary blade and normally in engagement with the spring for controlling movement of the blade.
3. A device of the character described, 20 comprising a primary and an auxiliary blade, said primary blade provided with a stirrup at one end, said stirrup having an opening formed therein, parallel, integral extensions formed upon said stirrup, a spring secured 25 upon one side of said stirrup and projecting into the opening formed therein, a stirrup secured to said auxiliary blade near one end, and a finger formed upon said stirrup and normally engaging the portion of the spring 30 projecting into the opening of the stirrup carried by the primary blade.

4. A device of the character described, comprising a primary and an auxiliary blade,

a stirrup having a rectangular opening secured to said primary blade at its lower end, 35 an angular spring secured near one end of said stirrup and projecting into said opening, said stirrup provided with parallel extensions projecting at right angles thereto, the auxiliary blade journaled upon said parallel extensions, a stirrup secured to the lower end of said auxiliary blade, a finger secured to said stirrup adapted to engage the inner face of said spring and slide longitudinally over a portion of the inner face of the same, when 40 lateral movement is imparted to one of said blades.

5. In a device of the character described, the combination of a primary blade, a stirrup provided with an opening carried by said 50 blade, said stirrup provided with extensions, a spring carried by said stirrup and extending into the opening thereof, an auxiliary blade provided with a stirrup, pivotally mounted upon said extensions, and a finger 55 formed upon said stirrup carried by the auxiliary blade, the finger adapted to engage said spring.

In witness whereof I have hereunto signed my name, this 28th day of June, 1904, in the 60 presence of two subscribing witnesses.

GEO. BURROWS.
